Primary Examiner—Wallace R. Burke*Assistant Examiner*—Joel Sincavage*Attorney, Agent, or Firm*—Sughrue, Mion, Zinn, Macpeak & Seas**[57] CLAIM**

The ornamental design for a programmable electronic cam-operated switch, as shown and described.

DESCRIPTION

FIG. 1 is a front, top and right side perspective view of a programmable electronic cam-operated switch showing our new design;

FIG. 2 is a front elevational view thereof;

FIG. 3 is a top plan view thereof;

FIG. 4 is a right side elevational view thereof, the opposite side being a mirror image thereof;

FIG. 5 is a rear elevational view thereof with the broken line showing included for the purpose of illustrating environmental structure which forms no part of the claimed design; and,

FIG. 6 is a bottom plan view thereof.

FIG. 1

FIG. 2

FIG. 3

*FIG. 4**FIG. 5**FIG. 6*
